TRUNKING SYSTEM OF RADIODISTRIBUTION

Original Filed Jan. 21, 1925 2 Sheets-Sheet 2

Inventor

Edward Eblement

UNITED STATES PATENT OFFICE.

EDWARD E. CLEMENT, OF WASHINGTON, DISTRICT OF COLUMBIA; ASSIGNOR TO EDWARD F. COLLADAY, OF WASHINGTON, DISTRICT OF COLUMBIA.

TRUNKING SYSTEM OF RADIODISTRIBUTION.

Original application filed January 21, 1925, Serial No. 3,861. Divided and this application filed February 19, 1926. Serial No. 89,411.

The present application is a division of my prior copending application Serial No. 3,861, filed January 21, 1925, patented March 16, 1926, No. 1,577,108. It relates to systems of radio broadcast distribution and has for its object to organize such a system so that a program may be originated, relayed and distributed over a larger area, uniformly and in a systematic and orderly manner to authorized users or subscribers, who may select any one of a plurality of programs being transmitted simultaneously, without complicated apparatus at the subscribers' stations, the tubes used by the subscribers in receiving being all preferably located at central points where supervision, maintenance, power supply and control may be centralized under the care of expert operators. In my said prior application, a district station is described, which distributes the program or programs to a plurality of local central stations, which in turn distribute the broadcast matter to their respective groups of subscribers; and the distribution as specifically disclosed is over wire circuits to the subscribers' stations. The present application is not necessarily limited to a system employing a district station, the invention relating more particularly to the circuit and switching means connected to the subscriber's line at the local central station, and other features which will sufficiently appear hereinafter.

The invention is applicable to manual, automatic or so-called semi-automatic or automanual telephone systems, and while I shall describe herein distribution over the subscribers' lines at audio frequency only, it will be understood that superaudio frequencies may be employed as well, by providing the necessary tuned device at the central station, and the necessary detector instrument at the subscriber's station. Such a change is within the scope of any person skilled in this art, after reading the description of my system, and is therefore within the scope of the invention.

My invention is illustrated in the accompanying drawings, in which:

Fig. 1 indicates diagrammatically the telephone exchange portion and the broadcast equipment on the radio switchboard corre-

distributing portion of a subscriber's central station forming part of my system.

Fig. 2 is a diagram showing an arrangement of circuits and apparatus affording selection of a plurality of programs.

Referring to the drawings in detail and first to Fig. 1, this shows the essential circuits of an ordinary telephone exchange system in which J—J' are line terminal jacks forming the terminals of telephone lines leading to stations to be interconnected such as the subscriber's station A'. The central office terminals of each line are provided with the usual line relay L', line lamp L² and cut-off relay L³. Where service is to be metered a recording meter M is also individually associated with the line. In addition to the usual line terminal, multiples 1, 2 and 3, representing multiples of the tip, sleeve and test or cut-off circuits, respectively, I provide a fourth conductor 4 leading from a contact on the line relay along with the multiple conductors 1, 2 and 3 to the broadcast distributing system diagrammed in Fig. 2.

Referring to Fig. 2, a selective switch S is provided, stepped around by means of an electromagnet 420, controlled through front contacts 310 by the relay 42 which is included in the line circuit of battery B when the contacts of the line switch 9 are closed by the radio operator. The selective switch S contains bank contacts s—s'—s² connected to separate busses 27—28 (carrying No. 1 program), 270—280 (carrying No. 2 program), and 2700—2800 (carrying No. 0 or announcements). The switch S does not need to be restored to zero, and may be left always in the last position to which it has been moved, since the wires 25—26 leading to the wiper arms s³ of the switch are cut off at the relay contacts 23—24 when the apparatus is in disuse. The No. 1 and No. 2 program busses are connected to the output circuits of broadcast relay receivers 29—290 respectively, and the announcement bus 2700—2800 is connected to a local distributing apparatus or amplifier with a microphone M^f. The announcement set as a whole is shown symbolically only at AS. This position or

100 equipment on the radio switchboard corre-

sponds to the information operator's position on a telephone switchboard.

The operation is as follows: The subscriber calls by making short closures of his line at the key 63, after inserting the plug P^2 in the jack J^2 . These short closures flash both the telephone and the radio switchboard lamps L^2 (Fig. 1) and 36 (Fig. 2). Connection is established by the radio operator inserting the plug 10 in the jack 9, or closing the equivalent switch. It may be mentioned in passing that any form of switch may be substituted for the jack 9, even to a relay controlled from a keyboard position by the operator, without departing from the invention. Divers forms of switches suitable for this purpose will occur to those skilled in the art, such as for example a key switch of the general type of operator's ringing and listening key, having pivoted lever and a rocking wedge passing up and down between the pairs of contact springs, to open and close them. Such a switch may have practically any desired number of contacts, and requires no separate plug to operate it. The additional contacts are available for a number of purposes, including the cut-off of battery current from the magnet 420 when the parts are in disuse, which should be done as a matter of good practice, although not necessarily a part of the invention.

The subscriber's line having been thus connected with the central office wires 1-2, the relay 42 is included therein, and comes under the control of the subscriber. Since his line circuit remains closed after signaling at the key 63, the relay 42 is energized and closes all its contacts 310, 34, 24, 23 and 351. This connects the input or grid side of the line tube 37 to the switch wipers s^3 , and also closes the filament circuit through battery F^6 . The three pairs of bank contacts $s-s'-s^2$ represent a suitable number to contain all the program busses, and if it be desired to use a circle of contacts greater in number than the number of busses, then the latter may be repeated several times in passing around the circle. The switch wipers are left where they stand without restoring, so that when the subscriber has become connected through the tube 37 to the switch S he is immediately on some bus. If it is a program bus and he desires to select some particular item, he can by means of his key 63 propel the switch arms s^2 until they come in contact with the bank contacts s^2 connected to the announcer's bus 2700-2800, and by listening, he will hear a continuous announcement of the items then upon the bus, the items to follow, the numbers or call letters of the stations from which the said items are being sent, and any other interesting information connected with the same.

I consider this separate announcement bus,

corresponding to an information operator's position, to be important as well as novel and original with myself, and shall claim the same accordingly. Having ascertained what program and what items he desires to hear, the subscriber is able to start from zero and step the switch around to the desired busses such as 27-28, 270-280, etc. Thus the announcer's bus, when reached, which is always easily distinguishable, serves a double purpose, being also the zero bus from which the program busses are counted. If the subscriber has a loud speaker, and desires some particular item for which he has to wait, he may leave his switch connected with the announcer's bus until the time for making connection arrives, and in the meantime will receive all the announcements with such matters of entertainment and information as may be intercollected therebetween. This means that during the entire broadcasting period, the announcements will be going on, interspersed with comments, explanations, etc. To these may be added news items and the like if desired, but I think it preferable to have these on a separate program bus leaving the announcer's bus to fulfil the functions of an information operator only.

I have shown herein in Fig. 1 a meter connected to the test or cut-off wire 3, and for telephone recording this would be operated in the usual manner. For metering the radio service, I have shown in Fig. 2 the commutator and high voltage generator adapted to meter operation, in a manner familiar to those skilled in the art. This generator is only connected when the relay 42 is energized and the commutator closes the circuit, which occurs at intervals during the time the subscriber's line is connected to the radio bus or busses, but it is to be understood that where there is selection of program, there should also be selection of a charging rate corresponding thereto; which means that there would be a separate meter commutator for each of the program busses, brought into connection with the contacts 34 and test wire 3 through bank contacts of the switch S , corresponding to the program contacts $s-s'-s^2$ associated therewith by adjusting these separate commutators to different speeds or rates of operation, the metering can be made variable, according to the program being received. This is described and claimed in my prior copending applications, Serial No. 746,357, filed October 28, 1924, patented July 5, 1927, No. 1,635,153, and Serial No. 746,358, filed October 28, 1924, patented June 5, 1928, No. 1,672,372. Any method of differential metering may be employed for this purpose without departing from the scope of my invention.

It should be stated in closing that while I

have developed herein a specific arrangement of the apparatus and circuits for the purposes stated, there are a number of modifications which I contemplate and shall not describe herein specifically, because they will form the subject matter of separate applications. I wish to state herein however, that according to one modification, the line signal lamp 36 on the radio switchboard, and the line vacuum tube 37 on the same, may be made one and the same unit. The tubes 37 under proper conditions of lighting and arrangement may very well be used for visible signals. According to this arrangement, when a subscriber calls radio, he will flash the filament of the tube 37, which gives the visible signal to the radio operator that he desires radio connection.

While I have herein described and illustrated the use of audio frequencies for distribution to the subscribers over their wired line circuits the invention is not limited to such frequencies, but may employ also superaudio frequencies, so long as they are suitable for line transmission. In the work heretofore done by Major General Squier and others, frequencies ranging from 25 to 100 kilocycles per second have been found suitable for this purpose. In order to make such frequencies available for distribution among the subscribers in the present system, the connections from the central station receiving and relay distributing apparatus remain practically the same as those described and shown in Fig. 2, the input or grid circuit of the individual line tube 37 also remaining the same. The repeating coil connection to each line must either be supplemented or replaced however by a filter connection, preferably permanent, which will permit superaudio frequency currents to be transmitted from the plate circuit of the tube to and over the line circuit to the subscriber's station, while the battery current from the battery B will simultaneously flow over the subscriber's line for signaling and talking purposes of the subscriber. At the subscriber's station, complementary connections must be made, and a detector radio set must be connected to receive superaudio currents over the line, while the telephone elements are connected, preferably in parallel, to receive the battery current and transmit and receive audio frequency waves. Such an arrangement is shown as to its principles in Letters Patent granted me January 6, 1925, No. 1,522,362, to which reference is had for further explanation of the principles involved.

The words "telephonic relay" used in the claims hereinafter are to be understood as meaning a relay including as one element a vacuum tube or the equivalent thereof for relaying potential and current variations such as those generated in accordance with

sound waves, said current variations being adapted to act upon means to reproduce the original sound waves.

What I claim is:

1. In a system of broadcast distribution, a telephone central station, having subscribers' substations with wire lines interconnecting them, a plurality of broadcast busses at the central station, telephonic relay means of the type described at the central station, individual to each subscriber's line, a rotary step-by-step selector switch having a set of wipers arranged to successively engage a plurality of sets of contacts in repeating cycles, different sets of contacts being connected with said different broadcast busses, means at the central office for connecting said switch to a line when calling, and controlling means at the subscriber's substation for stepping said switch forward.

2. In a system of broadcast distribution, a telephone central station, having subscribers' substations with wire lines interconnecting them, a plurality of broadcast busses at the central station, telephonic relay means of the type described at the central station, individual to each subscriber's line, each subscriber's individual telephonic relay having selective switching means whereby it may be connected to said busses one at a time in succession and in recurring cycles, and means for controlling said switching means from its associated substation.

3. The system claimed in claim 2 in which all but one of the broadcast busses are permanently connected during operation to broadcasting means to supply programs, and an announcer's transmitter and associated apparatus permanently connected during operation to the remaining bus, to furnish announcements relating to the programs supplied by the other busses.

4. The system claimed in claim 2 in which the switch is a non-restoring or uni-directional switch and disconnection is effected between the switch and the input side of the telephonic relay means.

5. The system claimed in claim 2, with means at the central station for connecting a supervisory relay in series with a subscriber's line, said supervisory relay being responsive to current changes in the subscriber's line to connect and disconnect the switch from the first mentioned telephonic relay means.

6. The system claimed in claim 2, having a relay controlling the selective switching means, a vacuum tube amplifier as said telephonic relay means, and a repeating coil between said tube and the line, said relay, tube, and coil being associated together as a working group or unit, and having the input and output circuits of a group controlled by the subscriber.

7. A broadcasting exchange system, com-

- prising a central station and subscribers' stations, with line wires interconnecting them, a plurality of switching busses or terminals at the central station, means to supply different programs thereto, and a selective relay and amplifier set for each line comprising a unidirectional non-restoring switch having a pair of wipers engaging a plurality of pairs of bank contacts in sequential order 10 and in recurring cycles, circuit connections from said bank contacts to said switching busses or terminals, circuit connections from said wipers to the input side of said amplifier, other circuit connections from the 15 output side of said amplifier to terminals of the associated line, and means controlled over the line by the subscriber to actuate and to stop said switch at will, for the purpose of selecting a desired program or of disconnecting the line from the program busses, said means also acting to control the program transmission circuits between said switch contacts and the input side of said amplifier.
- 25 8. In a system of the class described, a plurality of program busses, a step by step switch containing bank contacts connected to said busses respectively, subscribers' lines and means including a vacuum tube relay 30 for connecting said switch to a line, with controlling means at the subscriber's station for stepping said switch in a selection of program, also for disconnecting said switch and program busses from the line and for activating and disabling said vacuum tube 35 relay at will.
9. A system of the class described having a plurality of program busses, subscribers' lines, and a step by step switch containing bank terminals of said program busses and 40 having means controlled by a subscriber for stepping its wipers and for connecting the same to the subscriber's line, together with a unidirectional vacuum relay included in said line connection and also controlled by the 45 subscriber.
10. A system of the class described having a plurality of program busses, subscribers' lines, a step by step switch containing bank terminals of said program busses and 50 having a pair of wipers cooperating therewith, a program repeating relay between said wipers and a subscriber's line, means between the said repeating relay and the line for connecting said relay and the switch to 55 line, and contact means between the switch and said repeating relay controlled by the subscriber for connecting and disconnecting said switch to and from said repeating relay and thereby to and from the line. 60

In testimony whereof I hereunto affix my signature.

EDWARD E. CLEMENT.
